(57) **CLAIM**

The ornamental design for a stamp for protecting personal information, as shown and described.

DESCRIPTION

FIG. 1 is a front right side perspective view of the stamp, showing our new design with the cap in place;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front right side perspective view of the stamp with the cap omitted in order to show aspects of the design not otherwise apparent;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof; and,

FIG. 14 is a bottom plan view thereof.

The broken lines depict portions of the stamp that form no part of the claimed design.

1 Claim, 14 Drawing Sheets
